UNITED STATES PATENT OFFICE

163,553

COMBINED TELEVISION SCREEN WINDOW
FRAME AND CONTROL UNIT

Samuel E. Adler, Chicago, Ill., assignor to Admiral Corporation, Chicago, Ill., a corporation of Delaware

Application March 3, 1951, Serial No. 14,381

Term of patent 14 years

(Cl. D56—4)

To all whom it may concern:

Be it known that I, Samuel E. Adler, a citizen of the United States, residing at Chicago, in the county of Cook, State of Illinois, have invented a new, original, and ornamental Design for a Combined Television Screen Window Frame and Control Unit, of which the following is a specification, reference being had to the accompanying drawings, forming part thereof.

Fig. 1 is a front elevational view of a combined television screen window frame and control unit, showing my new design;

Fig. 2 is a top plan view of the same;
Fig. 3 is a sectional view on line 3—3 of Fig. 1;
Fig. 4 is a sectional view on line 4—4 of Fig. 1;
Fig. 5 is a sectional view on line 5—5 of Fig. 1; and

Fig. 6 shows the unit in end elevation when viewed from the right of Fig. 1.

The dominant features of my new design reside in that part shown by full lines of the drawings.

I claim:

The ornamental design for a combined television screen window frame and control unit, as shown and described.

SAMUEL E. ADLER.
